REACTANCE COMPENSATION SYSTEM

George H. Brown, Princeton, N. J., assignor to
Radio Corporation of America, a corporation of
Delaware

Application February 14, 1945, Serial No. 577,912

8 Claims. (Cl. 178—44)

1

This invention relates to reactance compensation and more particularly to improvements in the art of neutralizing the effects of series reactances in radio frequency power circuits. As is well known to those skilled in the art, the frequency band width throughout which a radio frequency transmission circuit operates efficiently to transfer power is an inverse function of the series reactances present in the circuit.

The principal object of the present invention is to provide improved methods of and means for compensating the effects of such series reactances.

Another object is to provide improved methods of and means for obtaining broad band operation of radio frequency power circuits.

A further object is to provide an improved rotatable joint structure for radio frequency transmission systems, wherein series reactances produced by overlapping coaxial conductors are effectively neutralized throughout a wide frequency band.

These and other objects will become apparent to those skilled in the art upon consideration of the following description, with reference to the accompanying drawing, of which

Figure 1 is a schematic diagram of a power transmission circuit embodying the invention,

Figure 2 is a group of graphs illustrating the effects of varying the characteristic impedance of one of the transmission line elements in the circuit of Figure 1,

Figure 3 is a further group of graphs illustrating the design of the circuit of Figure 1,

Figure 4 is a schematic diagram of a rotatable joint in accordance with prior art practice, and

Figure 5 is a schematic diagram of a rotatable joint constructed in accordance with the present invention.

Referring to Figure 1, it is assumed that a load 1, of impedance Z_0 is to be energized from a source 3, also of impedance Z_0 , through a transmission line 5 having a characteristic impedance Z_0 . In the absence of any further circuit elements, the load 1 and line 5 will be matched to the source 3 at all frequencies, providing efficient power transfer independently of frequency. It is assumed, however, that it is necessary to connect in series with the load 1 a reactance element, represented in the present illustration by a transmission line section 7, open circuited at its free end.

Open-circuited transmission lines exhibit, at certain frequencies, characteristics similar to those of series resonant circuits. Thus, at the

2

frequency at which the line 7 is one quarter wavelength long, a very low impedance is presented by it in series with the load 1. At lower frequencies, the line 7 acts like a capacitance connected in series with the load 1, while at higher frequencies the line 7 presents an inductive reactance in series with the load 1. As long as the reactance of the line 7 is very much lower in magnitude than the impedance Z_0 of the load 1, there is substantially no impedance mismatch caused by the presence of the line 7. However, at frequencies outside a certain relatively narrow band, the reactance of the line 7 will be of the same order of magnitude as the impedance Z_0 , or higher. At any of these frequencies, a major portion of the voltage of the source 3 will appear across the line 7 rather than the load 1, causing serious impedance mismatch and preventing efficient transfer of energy.

No great amount of energy is dissipated in the line 7 under the foregoing conditions. The current is reflected back down the line 5 to the source 3. Denoting the current transmitted by the source 3 as i_1 , and the reflected current as i_2 , the absolute value of

$$\frac{i_2}{i_1}$$

30 is the reflection coefficient K . The degree of impedance match is commonly expressed in terms of standing wave ratio R where

$$R = \frac{|i_1| - |i_2|}{|i_1| + |i_2|}$$

35 Referring to Figure 2, the standing wave ratio on the line 5 is a function of frequency, when supplying the load 1 shunted by the line 7 without compensation, as represented by the solid curve A. The ratio f/f_0 represents the departure from the resonant frequency of the line 7, that is f_0 is the resonant frequency of the line 7 and f is the actual frequency of the energy being transmitted. It is seen that at resonance the standing wave ratio is unity, indicating that no reflection occurs. At all other frequencies, R is less than 1, increasing with the departure from f_0 . The curve of A, as well as the other curves of Figure 2, is based on the assumption that the characteristic impedance of the line 7 is one-half the impedance of the load 1.

In accordance with the present invention, the line 5 terminates in a line section 9 of one-half wavelength at the resonant frequency of the line 7, and of impedance Z_0 . A quarter wave line 11,

electrically identical with the line 7, is connected across the junction between the lines 5 and 9. It is found that by adjusting the surge impedance Z_c of the line section 9 to the proper value, the standing wave ratio may be maintained substantially equal to 1 over a wide range of frequencies. The curves B, C and D of Figure 2 show how the ratio R varies with frequency with values of

$$\frac{Z_0}{1.1}, \frac{Z_0}{1.2}, \frac{Z_0}{1.3}$$

respectively for the surge impedance Z_c of the line section 9. It is seen that with

$$Z_c = \frac{Z_0}{1.1}$$

the standing wave ratio remains higher than .9 throughout the range $.57f_0$ to $1.43f_0$. With

$$Z_c = \frac{Z_0}{1.2}$$

the ratio R remains substantially constant at unity from $.75f_0$ to $1.25f_0$. The preferred value for Z_c probably lies somewhere between

$$\frac{Z_0}{1.1} \text{ and } \frac{Z_0}{1.2}$$

providing a standing wave characteristic inter-

$$(6) \quad Z_i = Z_c \left[\frac{\left[\sin \left(\frac{\rho}{2} \right) \tan \rho - \cos \left(\frac{\rho}{2} \right) \right] \tan \rho \tan \left(\frac{\rho}{2} \right)}{Z_0 Z_s} + \frac{\left[\cos \left(\frac{\rho}{2} \right) \tan \rho + \sin \left(\frac{\rho}{2} \right) \right] \sin \left(\frac{\rho}{2} \right)}{Z_c Z_s} + \right. \\ \left. \frac{\left[\tan \rho \sin \left(\frac{\rho}{2} \right) \right]^2 + \left[\cos \left(\frac{\rho}{2} \right) \tan \rho + \sin \left(\frac{\rho}{2} \right) \right]^2}{Z_c Z_s} \right. \\ j \left[Z_c \left[\frac{\left[\sin \left(\frac{\rho}{2} \right) \tan \rho - \cos \left(\frac{\rho}{2} \right) \right] \left[\cos \left(\frac{\rho}{2} \right) \tan \rho + \sin \left(\frac{\rho}{2} \right) \right]}{Z_0 Z_s} - \frac{\tan \rho \sin^2 \left(\frac{\rho}{2} \right)}{Z_c Z_s} - \frac{Z_s}{\tan \left(\frac{\rho}{2} \right)} \right] \right. \\ \left. \left[\tan \rho \sin \left(\frac{\rho}{2} \right) \right]^2 + \left[\cos \left(\frac{\rho}{2} \right) \tan \rho + \sin \left(\frac{\rho}{2} \right) \right]^2 \right] + \frac{Z_s}{\tan \left(\frac{\rho}{2} \right)}$$

mediate those shown by curves B and C. Curve D shows clearly that

$$\frac{Z_0}{1.3}$$

is outside the preferred range of values for Z_c .

Families of curves similar to those of Figure 2 may be calculated and plotted for other ratios of the impedance of the line 7 to the impedance of the load 1. From such families of curves the flattest curve, corresponding to the curve C of Figure 2, may be selected to determine the correct ratio

$$\frac{Z_0}{Z_c}$$

for providing optimum reactance compensation. This has been done, and the results are illustrated by the curve E of Figure 3. The abscissa of the graph of Figure 3 is

$$\frac{Z_s}{Z_0}$$

where Z_s is the surge impedance of the quarter wave line sections 7 and 11, and Z_0 the impedance of the load 1. From the curve E the proper value of the impedance Z_c in terms of the load impedance Z_0 may be selected. Although the lines 5, 7, 11 and 9 are illustrated schematically in Figure 1 as parallel open-wire lines, it is to be understood that any or all of the above lines may be of coaxial construction.

Denoting the electrical length of the line section 9 as ρ , and that of the lines 7 and 11 as $\rho/2$, the impedance looking toward the load from the point a in Figure 1 is:

$$(1) \quad Z_a = Z_0 - jZ_s \cot (\rho/2) = Z_0 \left[1 - j \frac{Z_s}{Z_0} \cot (\rho/2) \right]$$

The impedance looking into the line section 9 from the point b is:

$$(2) \quad Z_b = \frac{Z_a + jZ_c \tan \rho}{Z_c + jZ_a \tan \rho} Z_c$$

The impedance looking into the line section 9 through the series-connected line section 11 is:

$$(3) \quad Z_t = Z_b - jZ_s \cot (\rho/2)$$

Substituting Equation (1) in Equation (2), and Equation (2) in Equation (3):

$$(4) \quad Z_t = \frac{Z_0 \left[1 - j \frac{Z_s}{Z_0} \cot (\rho/2) \right] + jZ_c \tan \rho}{Z_c + jZ_0 \tan \rho \left[1 - j \frac{Z_s}{Z_0} \cot (\rho/2) \right]} Z_c - jZ_s \cot (\rho/2)$$

The impedance Z_t includes a resistive component R_t and a reactive component X_t :

$$(5) \quad Z_t = R_t + jX_t$$

Separating the real and imaginary components of Equation (5):

45 The first term is R_t and the second term is X_t . By Equation (6), the values of Z_t , R_t and X_t may be computed for any values of Z_s , Z_0 and Z_c .

The standing wave ratio may be calculated as mentioned above from the direct and reflected currents i_1 and i_2 .

$$(7) \quad i_1 = A \left[1 + \frac{R_t}{Z_0} + \frac{jX_t}{Z_0} \right]$$

$$(8) \quad i_2 = A \left[1 - \frac{R_t}{Z_0} - \frac{jX_t}{Z_0} \right]$$

where A is a constant. The curves of Figure 2 are calculated by substituting the indicated values of Z_c , Z_0 and Z_s in the above Equations (6), (7) and (8) to determine the currents i_1 and i_2 for computing the standing wave ratios.

By differentiating the expression for X_t in Equation (6) with respect to ρ , substituting $\rho = \pi$ radians, setting

$$(6) \quad \frac{d(X_t)}{d\rho} = 0$$

and solving for

$$70 \quad \frac{Z_0}{Z_c}$$

$$(9) \quad Z_c = \frac{1 + \sqrt{1 + 4 \left(\frac{Z_0}{Z_s} \right)^2}}{2 \frac{Z_0}{Z_s}}$$

This represents the value of

$$\frac{Z_0}{Z_c}$$

which provides zero rate of change of X_1 with frequency. Equation (9) is represented graphically by the line F of Figure 3. It is seen that the curve F deviates from the curve E by a varying amount, up to about 10 percent at

$$\frac{Z_0}{Z_c} = 1$$

This is accounted for by the fact that the standing wave ratio curve which is flattest at f_0 , where $\rho = \pi$, is not necessarily the flattest throughout an appreciable range. Since the values of

$$\frac{Z_0}{Z_c}$$

represented by the curve E were determined by inspection of families of curves like that of Figure 2, it is probable that the optimum value for

$$\frac{Z_0}{Z_c}$$

for a given set of conditions, lies somewhere between that indicated by the curves E and F of Figure 3.

The above-described method of reactance cancellation may be applied to the design of a rotatable joint for radio frequency lines. Referring to Figure 4, a rotatable coaxial joint constructed in accordance with prior art practice comprises two concentric line sections 21 and 23 arranged so that their inner conductors and outer conductors respectively overlap by a quarter wavelength, at the mean operating frequency. The diameter of the outer conductor 25 of the line 21 is slightly less than that of the outer conductor 27 of the line 23, so that the conductors 25 and 27 are closely adjacent to each other, throughout the overlapping portion but do not touch. The inner conductor 29 of the line 23 is hollow at least through the overlapping portion, having an inner diameter slightly greater than the diameter of the inner conductor 31 of the line 21.

In the operation of the structure of Figure 4, the overlapping outer conductors 25 and 27 constitute a low impedance concentric line, open-circuited at its outer end 33. Owing to the impedance inversion characteristics of quarter wave lines, the open circuit at the point 33 is reflected as a short circuit at the point 35, thus effectively connecting together the outer conductors 25 and 27 at this point. Similarly, the inner conductors act as a low impedance quarter wave line open-circuited at the point 37, and presenting a short-circuit at the point 39. Thus at the frequency for which the structure is designed, the inner conductors 29 and 31 are effectively connected together at the point 39.

If the clearances between the overlapping portions of the conductors of the lines 21 and 23 are relatively small, the characteristic impedances of the quarter wave open-circuited lines are low, and the impedances presented at the points 35 and 39 are substantially zero over a fairly wide frequency range. The width of the band for which a structure like that of Figure 4 can be designed depends upon how close the tolerances may be maintained upon the diameters of the overlapping conductors.

Considerable improvement in the operation of

devices such as that illustrated in Figure 4 may be obtained by staggering the inner and outer overlaps, so that reactance at the point 35 is inverted to resonate with that at the point 39, and vice versa, as described in copending U. S. application Ser. No. 494,617, filed July 14, 1943 by D. W. Peterson and entitled Radio frequency rotating joint. However, the operating band width is still limited by the minimum clearances which are practical.

In accordance with the present invention, a wider usable frequency range may be obtained with a given clearance than with the above described structures, or the same frequency ranges may be secured with considerably greater clearance. Referring to Figure 5, two concentric line sections 121 and 123 are arranged so that their inner conductors and outer conductors are respectively overlapping by $\frac{1}{4}$ wavelength at the mean operating frequency, as in the system of Figure 4. However, the overlapping portions are spaced apart longitudinally, so that the inner end 135 of the overlapping portion of the outer conductors 125 and 127 is one-half wavelength distant from the end 139 of the overlapping portion of the inner conductors 129 and 131. The final half wavelength portion 141 of the outer conductor 125 cooperates with the final half wavelength portion 143 of the inner conductor 129 to function as a half wavelength coaxial line section connected between the points 135 and 139. This section corresponds in function to the half wavelength line section 9 in the circuit of Figure 1. The quarter wavelength overlapping portion of the inner conductors 131 and 129 corresponds to the line section 7 of Figure 1. Similarly the quarter wave overlapping portion between the outer conductors 125 and 127 corresponds to the line 11 of Figure 1.

The diameters of the conductors 125 and 131 are proportioned to provide a characteristic impedance Z_0 equal to that of the remainder of the transmission circuit (not shown). The diameters of the conductors 129 and 127 are similarly proportioned to provide a characteristic impedance Z_0 . The clearances between the outer conductors 125 and 127 and the inner conductors 129 and 131 are made as small as conveniently practical. The inner diameter of the half wave section 141 and the outer diameter of the half wave section 143 are proportioned to provide the proper characteristic impedance Z_c in accordance with the information illustrated graphically in Figure 3. The device of Figure 5 will operate throughout a relatively wide band of frequencies without introducing substantial reflection.

Although the invention has been described as embodied in a rotatable joint for coaxial transmission lines, it is not limited thereto, but may be similarly applied in substantially any case where an undesirable series-reactance is to be compensated. Briefly, the invention comprises the connection of a half wavelength transmission line to the point at which the reactance to be compensated appears. A reactance element substantially identical with that to be compensated is connected in series with the half wavelength line section at its other end. By adjusting the characteristic impedance of the half wavelength line in accordance with that of the reactance elements and the impedance of the transmission circuit, compensation is effected throughout a relatively wide band of frequencies.

I claim as my invention:

1. In a radio frequency network including a

load of impedance Z_0 , in series with an element which exhibits series resonant characteristics to energy of wavelength λ , and has a surge impedance Z_s , a system for compensating the reactance of said element throughout a band of frequencies, comprising a transmission line of length $\lambda/2$ and surge impedance Z_c , connected at one of its ends to said load, and a second element exhibiting series resonant characteristics identical with those of said first-mentioned element, connected in series with the other end of said line, the surge impedance Z_c of said line being such as to satisfy the relation:

$$\frac{Z_0}{Z_c} = \frac{1 + \sqrt{1 + 4 \left(\frac{Z_0}{Z_s} \right)^2}}{2 \frac{Z_0}{Z_s}}$$

2. In a radio frequency network including a source of impedance Z_0 , in series with an element which exhibits series resonant characteristics to energy of wavelength λ , and has a surge impedance Z_s , a system for compensating the reactance of said element throughout a band of frequencies, comprising a transmission line of length $\lambda/2$ and surge impedance Z_c , connected at one of its ends to said source, and a second element exhibiting series resonant characteristics identical with those of said first-mentioned element, connected in series with the other end of said line, surge impedance Z_c of said line being such as to satisfy the relation:

$$\frac{Z_0}{Z_c} = \frac{1 + \sqrt{1 + 4 \left(\frac{Z_0}{Z_s} \right)^2}}{2 \frac{Z_0}{Z_s}}$$

3. In a radio frequency network including a load of impedance Z_0 , in series with an element which exhibits series resonant characteristics to energy of wavelength λ , and has a surge impedance Z_s , a system for compensating the reactance of said element throughout a band of frequencies, comprising a transmission line of length $\lambda/2$ and surge impedance Z_c , connected at one of its ends to said load, and a second element exhibiting series resonant characteristics identical with those of said first-mentioned element, connected in series with the other end of said line, the surge impedance Z_c of said line being such that the quantity

$$\frac{Z_0}{Z_c}$$

has a value lying within the range of 90 percent to 100 percent of that of the quantity:

$$\frac{1 + \sqrt{1 + 4 \left(\frac{Z_0}{Z_s} \right)^2}}{2 \frac{Z_0}{Z_s}}$$

4. In a radio frequency network including a source of impedance Z_0 , in series with an element which exhibits series resonant characteristics to energy of wavelength λ , and has a surge impedance Z_s , a system for compensating the reactance of said element throughout a band of frequencies, comprising a transmission line of length $\lambda/2$ and surge impedance Z_c , connected at one of its ends to said source, and a second element exhibiting series resonant characteristics identical with those of said first-mentioned element, connected in series with the other end

of said line, the surge impedance Z_c of said line being such that the quantity

$$\frac{Z_0}{Z_c}$$

has a value lying within the range of 90 percent to 100 percent of that of the quantity:

$$\frac{1 + \sqrt{1 + 4 \left(\frac{Z_0}{Z_s} \right)^2}}{2 \frac{Z_0}{Z_s}}$$

5. A joint for connecting together two relatively rotatable coaxial transmission lines, comprising a pair of concentric tubular conductive members disposed in radially spaced overlapping relationship to each other and connected to the respective outer conductors of said two coaxial lines, a second pair of concentric conductive members disposed coaxially within said first pair of conductive members and in radially spaced overlapping relationship to each other, the end of the inner of said first two conductive members being spaced longitudinally along the axis of said lines a distance of substantially $\lambda/2$ from the end of the outer of said second pair of conductive members, where λ is the mean operating wavelength of the system, and the ratio of the inner diameter of said inner conductor of said first pair to the outer diameter of the outer conductor of said second pair being less than the ratio of the diameters of the outer conductors to the diameters of the inner conductors of said coaxial lines.

35. 6. A joint for connecting together two relatively rotatable coaxial transmission lines, comprising a pair of concentric tubular conductive members disposed in radially spaced relationship to each other overlapping through a distance of substantially $\lambda/4$ and connected to the respective outer conductors of said two coaxial lines, a second pair of concentric conductive members disposed coaxially within said first pair of conductive members and in radially spaced relationship to each other overlapping through a distance of substantially $\lambda/4$, the end of the inner of said first two conductive members being spaced longitudinally along the axis of said lines a distance of substantially $\lambda/2$ from the end of the outer of said second pair of conductive members, where λ is the mean operating wavelength of the system, and the ratio of the inner diameter of said inner conductor of said first pair to the outer diameter of the outer conductor of said second pair being less than the ratio of the diameters of the outer conductors to the diameters of the inner conductors of said coaxial lines.

7. A joint for connecting together two relatively rotatable coaxial transmission lines, comprising a pair of concentric tubular conductive members disposed in radially spaced overlapping relationship to each other and connected to the respective outer conductors of said two coaxial lines, a second pair of concentric conductive members disposed coaxially within said first pair of conductive members and in radially spaced overlapping relationship to each other, the end of the inner of said first two conductive members being spaced longitudinally along the axis of said lines a distance of substantially $\lambda/2$ from the end of the outer of said second pair of conductive members, where λ is the mean operating wavelength of the system, and the ratio of the inner diameter of said inner conductor of said first pair to the outer diameter of the outer con-

ductor of said second pair being such that the characteristic impedance Z_c between said last-mentioned two conductors is related to the characteristic impedance Z_s between the conductors of each of said pairs and the characteristic impedance Z_0 of said transmission lines so that the quantity

$$\frac{Z_0}{Z_c}$$

is within the range of 90 percent to 100 percent of the quantity:

$$\frac{1 + \sqrt{1 + 4 \left(\frac{Z_0}{Z_s} \right)^2}}{2 \frac{Z_0}{Z_s}}$$

8. A joint for connecting together two relatively rotatable coaxial transmission lines, comprising a pair of concentric tubular conductive members disposed in radially spaced relationship to each other overlapping through a distance of substantially $\lambda/4$ and connected to the respective outer conductors of said two coaxial lines, a second pair of concentric conductive members disposed coaxially within said first pair of conductive members and in radially spaced relationship to each other overlapping through a distance of substantially $\lambda/4$, the end of the inner of said first two conductive members being spaced longitudi-

nally along the axis of said lines a distance of substantially $\lambda/2$ from the end of the outer of said second pair of conductive members, where λ is the mean operating wavelength of the system, and the ratio of the inner diameter of said inner conductor of said first pair to the outer diameter of the outer conductor of said second pair being such that the characteristic impedance Z_c between said last two conductors is related to the characteristic impedance Z_s between the conductors of each of said pairs and the characteristic impedance Z_0 of said transmission lines substantially as follows:

$$15 \quad \frac{Z_0}{Z_c} = \frac{1 + \sqrt{1 + 4 \left(\frac{Z_0}{Z_s} \right)^2}}{2 \frac{Z_0}{Z_s}}$$
